UNITED STATES PATENT OFFICE

2,503,942

ADJUSTABLE HIGH CHAIR

Markus Engelberg and Goldie Engelberg,
Brooklyn, N. Y.

Application January 26, 1946, Serial No. 643,626

3 Claims. (Cl. 155—44)

1

This invention relates to adjustable chairs, and particularly although not exclusively to high-chairs.

It is primarily within the contemplation of our invention to enable a baby's highchair to be capable of such adjustment that it will conveniently accommodate infants of different heights, and in different positions. Most conventional high-chairs have either no adjustment features whatsoever, or have limited adjustability with respect to a single member, such as the position of the foot-rest. It is an important object of our invention to increase the utility of devices in this category by providing means not only for adjusting the position of the foot-rest, but also its length—as well as to provide an adjustable back-rest that will safely support the child in any desired position.

It is another important object of this invention to enable a highchair to be so adjusted so as to enable it to support a child either in a sitting position, or in a lying or recumbent position. The arrangement is hence such as to make it unnecessary to remove the child from the chair to a bed, inasmuch as our invention can be so manipulated as to enable the child to be accommodated in a restful a position, such as for sleeping purposes, as would be the case if he were transferred to a bed.

It is still a further object of our invention to provide means for safely maintaining the back-rest in any position. And it is another object of our invention to provide lateral walls which will provide safety barriers for the child when he is either in a sitting or reclining position.

It is also within the contemplation of our invention to provide simple and easily manipulable means for enabling the aforesaid adjustments to be made. And in this aspect of our invention it is a further important object to enable the back-rest and foot-rest portions to be simultaneously adjustable into coactive positions by a single manual manipulation.

And it is our objective to enable the above-mentioned features to be incorporated in a structure of relatively simple, readily fabricated and inexpensive design.

Other objects, features and advantages will appear from the drawings and the description hereinafter given.

Referring to the drawings,

Figure 1 is a front view of the preferred form of our invention.

Figure 2 is a side view thereof.

Figure 3 is a fragmentary side view of the seat 55. 37 of bar 36 constitutes an inner wall in adjacent

2

and back-rest portions in an intermediate reclining position.

Figure 4 is a fragmentary side view of the device when serving as a bed to accommodate the child in a lying position, the foot-rest being shown by dot-dash lines in an extended position.

Figure 5 is an enlarged fragmentary part-sectional view of the back-rest adjusting mechanism, substantially in the position shown in Figure 2.

Figure 6 is a back view of Figure 5.

Figure 7 is a bottom view, somewhat enlarged, of the linkage arrangement attached to the underside of the seat.

Figure 8 is a fragmentary bottom view of the foot-rest, looking up in the direction 8—8 of Figure 2, and

Figure 9 is a section of Figure 8 taken along line 9—9.

In the preferred form of our invention illustrated, the device contains a conventional leg arrangement 15 supporting the seat 16 and the back-rest 17 hingedly connected at 18 to the seat. Pivotally connected to the back-rest, and supported upon the two side walls 19 and 20 is the table portion 21. Swingably mounted upon rod 22 is the foot-rest portion 23, said rod being secured to the two front legs 24.

In the preferred construction of the foot-rest 23 there are embodied two tubular side members 25 movable as a unit by virtue of their attachment to the horizontal connector member 26, the tubes being apertured at their upper portions 27 through which the said rod 22 operatively extends. Telescopically extending within the tubes 25 are the rods 28, these being bent forwardly at substantially right angles to support the foot-board 29. The shanks of screw members 30 extend through and are in threaded engagement with the walls of tubes 25, the terminals of said screws 40 (not shown) being engageable with the inserted portions of the rods 28 to hold them in any selected position with respect to said tubes. The arrangement is hence such whereby the foot-board 29 can be adjustably moved with respect to the seat 16 and the back-rest 17, for accommodating infants of different heights.

Attached to back-rest 17 by suitable fastening means such as the wood screws 31 (Figure 5) is the bracket 32 containing two spaced, perforated walls 33 supporting the transverse shaft 34. Mounted over said shaft is the upper loop 35 of the bar 36, said loop being formed by making a return bend of the upper portion of the bar. The arrangement is such that the terminal portion 55 of bar 36 constitutes an inner wall in adjacent

and substantially parallel relation to the opposite downwardly extending portion 38 of bar 36. Extending through two aligned holes in portions 37 and 38 is the shank of the stud 39, the hand manipulable nut 40 being in threaded engagement with the shank of stud 39. The arrangement is hence such that upon an operative rotation of nut 40, portions 37 and 38 associated with loop 35 can be brought closer together or farther apart, thereby varying the width of the loop and permitting either a free sliding movement thereof with respect to shaft 34, or a tight frictional engagement of said looped portion with said shaft at any predetermined portion along the extent of the loop. It is of course obvious that the material of bar 36, or more particularly of the upper portion thereof, must be of resilient properties, the space 41 between walls 37 and 38 being such as to permit a free relative movement of the looped portion 35 with respect to shaft 34 when the nut 40 is in a retracted position.

The opposite or lower terminal portion 42 of bar 36 is pivotally mounted upon the bracket 43 attached to the underside of seat 16, the bracket containing two spaced walls 44 and 45 (Figure 7) supporting the transverse shaft 46 upon which is pivotally mounted the terminal portion 42 of bar 36. An intermediate portion 46a of said bar 36 is twisted substantially at right angles to the face of the bar; and pivotally attached at 47 thereto is the link 48 pivotally attached at 49 to the foot-rest 23.

It is apparent that upon a loosening of the handle or nut 40 and the rearward movement of back-rest 17, said back-rest can be brought to and firmly maintained at any desired position. It will further be observed that the pivotal movement of terminal 42 of bar 36 will simultaneously cause the link 48 to move the foot-rest 23 into an upward position. Upon a tightening of the handle or nut 40 both the back-rest 17 and foot-rest 23 will remain in a set position. It is also apparent that the bar 36 serves not only as an element in the linkage system above described, but also serves as a structural support for the back-rest 17 in any of its various positions.

It will be observed that in the upright position shown in Figure 2, the side walls 19 and 20 each have downwardly extending portions 50 overlapping the lateral sides of seat 16. When the back-rest is brought to the reclining position shown in Figure 4, the edge 51 of each of said portions 50 is substantially parallel and in adjacent relation to seat 16. It is thus apparent that side walls 19 and 20 constitute protective barriers for the child in any position of the chair.

The invention above-described embodies a structure which is not difficult of fabrication in that it consists of certain conventional features of highchairs together with an arrangement of linkages and other elements which, though novel, can be produced and assembled into place at a low cost.

In the accompanying drawings, the invention has been shown merely by way of example and in preferred form; but obviously many variations and modifications may be made therein which will still be comprised within its spirit. It is to be understood, therefore, that the invention is not limited to any specific form or embodiment, except insofar as such limitations are specified in the appended claims.

We claim:

1. In a highchair, a seat structure comprising a seat and forward and rear supporting legs

therefor, a foot-rest pivotally attached to the front portion of the seat structure, a back rest pivotally attached to the rear of the seat structure, a bracket attached to the rear of the back-rest and containing a horizontal shaft, a back supporting link the upper portion of which is bent back into the form of a loop with an elongated aperture through which the shaft extends and with which it is in pivotal and slidable engagement, the bent-back terminal of the link being movable with respect to the body of the link for varying the width of the loop, whereby the sides thereof may be brought into pressing engagement with the shaft to hold the link fixed with respect to the back-rest, the lower portion of the said link being pivotally attached to the seat structure, and another link the forward portion of which is pivotally connected to the foot-rest and the rear portion of which is pivotally connected to the said back supporting link intermediate the terminals thereof, whereby an operative pivotal movement of the back-rest will pivotally actuate the foot-rest.

2. In a highchair, a seat structure comprising a seat and forward and rear supporting legs therefor, a foot-rest pivotally attached to the front portion of the seat structure, a back-rest pivotally attached to the rear of the seat structure, a flat back supporting link bent substantially L-shaped, the upper portion of which is pivotally and slidably attached to the back-rest and the lower portion of which is pivotally attached to the underside of the seat, said lower portion having a part thereof twisted substantially at right angles to the flat surface of the bar, and another link the forward portion of which is pivotally connected to the foot-rest and the rear portion of which is pivotally connected to said twisted part of the back supporting link, whereby an operative pivotal movement of the back-rest will pivotally actuate the foot-rest.

3. In a highchair, a seat structure comprising a seat and forward and rear supporting legs therefor, a foot-rest pivotally attached to the front portion of the seat structure, a back-rest pivotally attached to the rear of the seat structure, two side walls attached to and extending forwardly from the lateral portions of the back-rest, said walls being in overlapping relation to the seat when the back-rest is in its upstanding position, and connecting means pivotally attached to the foot-rest and the back-rest, whereby an operative pivotal movement of the latter will pivotally actuate the former.

MARKUS ENGELBERG.
GOLDIE ENGELBERG.
